UNITED STATES PATENT OFFICE.

ROY E. TILLES, OF NEW ROCHELLE, NEW YORK, ASSIGNOR, BY MESNE ASSIGNMENTS, TO GOTHAM SILK HOSIERY COMPANY, INC., OF NEW YORK, N. Y., A CORPORATION OF DELAWARE.

IMITATION BOUQUET.

Application filed June 24, 1925. Serial No. 39,283.

To all whom it may concern:

Be it known that I, Roy E. Tilles, a citizen of the United States, residing at New Rochelle, New York, have invented new and useful Improvements in Imitation Bouquets, of which the following is a specification.

My invention relates to imitation bouquets, and contemplates the provision of a device of this character wherein a form is employed in conjunction with suitable articles of a fabric, or similar nature, to produce a striking imitation of a real bouquet of flowers. Another object of the invention is to provide a bouquet which is novel and attractive in appearance, and which for these reasons will materially increase the sales of the particular article forming the essential part of the bouquet.

To the accomplishment of the recited objects and others coordinate therewith, the preferred embodiment of my invention resides in the construction and arrangement of parts hereinafter described, illustrated in the accompanying drawings, and embraced within the scope of the appended claims.

In said drawings:

Figure 1 is a perspective view of the complete bouquet, and

Figure 2 is a perpendicular sectional elevation of the same.

Generally, my invention comprises a pre-arranged form having as a part thereof suitable foliage and designed to receive different numbers of articles, as stockings, handkerchiefs and the like, the articles being rolled upon themselves or otherwise arranged, and then inserted in the form so as to present an ensemble bouquet.

Referring more specifically to the drawings for a detailed description of my invention, numeral 5 designates a substantially cone-shaped hollow backing in which are nested any suitable number of smaller cone-shaped elements or pockets 6, the same being secured in their position in any convenient manner, as by means of an adhesive. In the present instance, six of the elements 6 are shown, although this number may be varied at will in accordance with the particular requirements.

Backing 5 is provided at its outer marginal edge with a fringe of foliage, 7, which for the purpose of illustration may comprise an imitation of ferns and other green leaves.

Each small cone is similarly equipped at its outer edge with foliage 8. A suitable handle 9, covered with green foil 10, is affixed to and depends from the backing 5.

In the present instance, the particular article which is received by the elements 6, is a stocking 11, as exhibited in the drawings. It is rolled spirally upon itself to simulate a rose, and then inserted in the receptacle. The same article may be arranged in imitation of a carnation or any other flower, and similarly combined with the form to produce the desired effect. Moreover, a piece of gauze or tulle as 12, may be tied in a bow at the outer extremity of the hand-piece 9. This adds to the attractiveness of the bouquet. Then, too, I find that flowers, such as roses and carnations, are best simulated by employing a fabric which is folded upon itself or tubular—as is the case with a stocking—for then the edges of the convolutions assume a natural contour, which may be still further improved by adept manipulation with the tips of the fingers. If a handkerchief were used it would be appropriately folded upon itself so that the edges of the convolutions presented to view would carry out the same scheme. This effect could not be obtained by using a single thickness of fabric.

It is to be understood that I am not to be limited to the precise means herein described for accomplishing the recited objects. For example, the bouquet is designed to portray any article other than stockings, handkerchiefs and the like, which may be practically combined with the form to produce the intended effect. Neither do I wish to be limited to the precise means for maintaining the articles in bunched or nested relationship as this means may be varied at will. I desire to reserve the right to effect such changes and modifications as may come fairly within the scope of the appended claims.

What I claim is:

1. As an article of manufacture, an imitation bouquet or the like comprising a backing, a plurality of substantially cone-shaped elements, nested with respect to said backing, each of said elements adapted to receive a fabric article arranged to simulate a flower, and foliage.
2. As an article of manufacture, an imita-

tion bouquet, or the like comprising a cone-shaped backing, a plurality of smaller cone-shaped elements, nested with respect to said backing, each of said elements adapted to receive a fabric article arranged to simulate a flower, and foliage.

3. As an article of manufacture, an imitation bouquet, or the like, comprising a backing, and a plurality of substantially cone-

shaped elements, nested with respect to said 10 backing each of said elements having a fringe of foliage, and adapted to receive a fabric article arranged to simulate a flower.

Signed at New York city, in the county of New York, State of New York, this 22nd 15 day of June, 1925.

ROY E. TILLES.
